Corporation, Hartford, Conn., a corporation of
Delaware

Application December 3, 1930, Serial No. 499,771
Renewed March 31, 1937

18 Claims. (Cl. 229—3.5)

This invention relates to bottles produced from viscous liquid plastic materials or dopes, including cellulosic derivatives. Other substances or combinations with cellulose derivatives in various states of viscosity and solution may also be used.

Specifically as related to the type of bottle which forms the subject matter of this invention, I contemplate the production of a bottle and a cap which may be used for carbonated beverages. Such a bottle may have a durable wall structure or may have walls of a softer, collapsible nature to suit particular requirements and uses. However, the invention is not limited to bottles for use solely for carbonated beverages; but many other types of bottles may be produced.

As it may be desirable to provide bottles formed in two parts to be assembled at the point of use, or as a single complete bottle ready for immediate use, suitable methods of making both types of bottles are herein disclosed.

Among the objects of the present invention is to provide a bottle formed of suitable plastic material, including cellulose derivatives, which will be less liable to breakage during use and handling than glass bottles now in common use and which has such other apparent advantages as are inherent from the construction of the bottle from tough, flexible, transparent and light weight material. However, other materials differing somewhat from cellulosic dopes in their nature may also be used. Solutions of cellulose acetate in and with various natural gums or resins, synthetic condensation products or nitro-cellulose, with or without modifying agents, may also be used in the processes and to form the articles hereinafter to be described.

With relation to the manufacture of a two-part bottle, which is to be assembled by the user to form a completed bottle, the invention provides a way of forming the mouth and neck portions of the bottle on the upper portion, while suitable rims or flanges are preferably provided at the adjoining ends of the two portions, which may be rolled together to form a shoulder flange on the completed bottle, the purpose being to strengthen the bottle and to provide an annular ledge around the largest diameter portion thereof upon which it may be supported during charging and capping operations.

A further object of the invention is to so coordinate the shape and configuration of the cap and the mouth of a bottle that a suitable engaging portion may be provided on the bottle for receiving the stopper type of cap herein disclosed.

In this connection, it is a specific object to so

arrange these parts in their relation to one another that internal pressure from a carbonated liquid will serve to produce an intimate seal between the edges and engaging portions of the bottle mouth and an associated stopper cap.

In making a relatively soft or collapsible bottle, it will be found necessary at times to have a suitable degree of rigidity in the upper portion of the bottle, for which reason and also to provide constrictions desired by users, the upper portion of the bottle may be press-formed from paper plastics or many other types of plastic compositions. In such a case, this portion of the bottle may be embossed, color-printed or otherwise labeled. However, as in most instances, sufficient stiffness can be imparted to the upper portion of the bottle by using cellulose materials, which likewise can be decorated, colored, labeled or embossed at the time of manufacture, such materials may be employed preferably because of their transparency and toughness. Exceptions to this rule may, however, be desirable for particular purposes or to satisfy particular users.

A bottle such as outlined in the preceding paragraph would have a transparent lower body portion showing the beverage contained, while the upper portion, which sometimes may be formed of opaque materials, will be slightly more rigid or reinforced by ribbing, for example, as herein-after disclosed relative to other parts of the bottle. Thus a cap may be applied to and removed from the mouth of the bottle without collapsing the adjacent body wall structure thereof.

It is thus an object of this invention to provide a composite bottle in the sense that different materials may enter into the construction of the walls of its several portions, one portion being made up of several coatings or laminations of different materials and having a greater thickness or firmness of structure than the other portion. Also, one part of the bottle may be opaque and the other part transparent, but of greater softness for certain purposes, so that a user may collapse the bottle after consuming its contents. In this connection, it is an object to provide a narrow neck bottle of collapsible structure for use at ball parks and other places where a glass bottle is undesirable or dangerous.

Another object is to provide conventionally shaped bottles of more rigid structure for bottling carbonated beverages, and also to provide bottles of different appearance for the bottling and sale of other carbonated drinks. While the type of bottle shown has a particular form and structure, the invention is not limited to this em-

bodiment as wide-mouth containers and jars may be manufactured by the means and methods herein disclosed.

Among the novel steps of the invention for the forming of bottles in separate parts or as a unitary bottle are the procedures of coating external or internal faces of molding implements with film-depositing liquid plastic materials or dopes, while negative or positive air pressures are used to control the fluid movements of the plastic materials or dopes relative to the film-receiving surfaces of the molds.

The invention also includes the forming of the bottle body or any hollow shape, in as far as its major wall surface is concerned, by a single coating of a molding implement with a viscous liquid plastic material or dope to produce a flexible wall, which is rendered stiff and serviceable by reinforcements, ribbings or other strengthening portions. In this connection with relation to forming a serviceable bottom wall for a bottle, it is an object of my invention to use vacuum communicated from within a molding element to the bottom-shaping surface upon which the plastic material is being deposited, such surface being provided with suitable recesses or grooves into which the liquid plastic material is caused to flow by differential pressure. As the plastic material solidifies in such grooves, there will be formed a wall or rib, which is integral with but at right angles to the bottom wall of the hollow container, which rib will act to buttress and prevent the easy collapse of the adjacent wall portion of the hollow shell-like body of the container. When used with the bottom wall proper of a bottle, the ribs will prevent distention or outward bulging when the bottle is filled or under internal pressure. Thus, this type of ribbing will aid in maintaining the desired shape and rigidity without increasing the overall thickness of the reinforced walls.

In another respect, it is the purpose of my invention to employ both vacuum action and air pressure in causing close surface adhesion of viscous plastic materials or dopes to the relatively smooth and polished surfaces of forming molds and in holding or releasing the inceptive film relative thereto. Also, suction may be used in withdrawing air from molding cavities, so that the coating material or dope may be drawn in to establish uniform contact with forming faces and thereby, for instance, to form the finished upper edge of a hollow container or the brim of a tumbler type of drinking vessel.

With relation to the dip-forming of the mouth of a bottle, it is an object of this invention to establish local control of the movement of a liquid plastic material at the point of deepest submersion of the mouth or lip-forming end of a molding element and to utilize variations in the fluid or air pressure application to govern the flow of the film-forming material and the extent to which it contacts with the lip or mouth-forming surface of the molding element. Such variations in the gaseous pressure over the surface of the liquid plastic material or dope may be employed to create alternate advancing and receding movements of the body of liquid plastic material or dope for depositing successive coatings or films on the lip or mouth-forming surfaces of the forming elements, so as locally to increase the thickness or general strength and toughness of the wall forming this portion of the bottle.

A principal object of the invention is to form from organic plastic materials, a bottle body comparable to bottles now being made of glass

and to provide in that body of plastic material all the advantages inherent in a glass bottle coupled with the additional advantages inherent from the use of relatively unbreakable plastic materials.

The light weight of the various plastics usable according to my present invention provides a considerable saving in packaging and freight costs over conventional glass bottles. Cellulosic materials are as transparent as glass and can be produced practically waterproof and odorless. The production of bottles in an economical way as is made possible by the processes employed in carrying out my present invention of producing hollow containers will afford new uses and open new markets for many plastic materials.

In the accompanying drawings, there are shown two types of bottles, which are the specific subject matter of this invention, and the means and methods of making both types.

Figure 1 is a view in vertical section of a bottle which was formed of two separate portions;

Fig. 2 is a view in vertical section of a similar bottle made in one part;

Figs. 3 and 4 are views in central vertical section showing caps or stoppers suitable for use respectively with the bottles shown in Figs. 1 and 2;

Figs. 5 and 6 are fragmentary views in central vertical section showing the bottles respectively illustrated in Figs. 1 and 2 with caps or stoppers therein;

Fig. 7 is a fragmentary view in central vertical section showing part of an apparatus for making the upper portion of a bottle of the two-part type of construction;

Fig. 8 is a composite fragmentary view principally in central vertical section showing an arrangement of apparatus which may be used for forming the main or lower body portion of a two-part bottle, this apparatus also being usable in making drinking cups by a similar method, the left hand half of this figure showing one construction for controlling the temperatures of the molding implement and the right hand half, another or modified construction for the same purpose;

Figs. 9 and 10 are views in central vertical section of the upper and lower portions respectively of a bottle, which portions together form a two-part bottle, the relative position of the figures indicating the arrangement of the bottle portions prior to their being assembled as a bottle;

Fig. 11 is a composite fragmentary view substantially in vertical section of an apparatus suitable for uniting the portions of a two-part bottle and illustrating the method employed, the left hand half of the figure illustrating a preliminary step in the process and the right hand half, the process of uniting the two bottle portions substantially completed;

Figs. 12 to 17 inclusive are a series of diagrammatic views in vertical section illustrating process steps and the relationship of a molding implement to a bath of liquid plastic material or dope during the formation of a one-piece bottle;

Fig. 18 is a composite fragmentary view illustrating a preferred method of compacting the shoulder wall formation of the one-part bottle to form a shoulder flange thereon, the left half of the figure showing the compacting about to begin and the right half, the compacting substantially completed; and

Fig. 19 is a fragmentary assembly view, principally in vertical section, illustrating one type of

arrangement for removing surplus plastic material from the mouth of a bottle.

A bottle 1, Fig. 1, is produced from two separate hollow body portions 2 and 3, these portions being united in a manner to produce a water and air-tight seal. The preferred way of uniting the two bottle portions is to use a combination of sealing dope or adhesive, local heat treatment and mechanical action as indicated in Fig. 11.

10 The bottle portions 2 and 3 are preferably formed by dipping suitable formers or molding implements into a liquid plastic material or dope to deposit a film of the liquid thereon, which may thereafter be rigidified in any suitable manner, 15 as by the evaporation of the volatile solvent from a viscous cellulosic dope, while it is spread as a film on the heated surfaces of the molding members, generally indicated at 4 and 11, Figs. 7 and 8. This film also may be formed from other suitable liquid plastic materials, which are capable of being rigidified by coagulation, condensation or otherwise, as a layer or film coating on the exterior or interior faces of suitable molding implements.

25 The several molding implements 4 used for shaping the upper portions 2 of bottles, Fig. 1, are submerged in a bath of liquid plastic material or dope 5 as indicated in Fig. 7. For this purpose, the liquid plastic material or dope 5 may be bodily elevated to effect the required amount of submersion or surface contact with one or several molding implements 4, while the latter are or may be kept relatively stationary. Such a method of applying the liquid plastic material or dope is advantageous where several different movements are otherwise to be given to such molding implements, Figs. 7 and 8, since by this means the mechanical operating means required may be simplified.

40 The film-receiving or molding implement 4 has a tubular passage 6 leading into an air bell cavity 7 at the lower end thereof. When the implement 4 is submerged, the air pressure in the cavity 7 may be controlled to keep the liquid plastic material or dope from rising above a certain predetermined level. In this way, there may be established an artificial level for the liquid plastic material or dope inside the cavity 7, so that only a predetermined desired portion of the inner face 45 of shell 8 of the implement 4 will be covered by the plastic material, Fig. 7. By this arrangement, the curved reentrant lip wall 9, Fig. 1, of the bottle mouth may be formed.

As it is desirable to impart greater strength to 55 the lip wall 9 of the bottle because of its intended association with a cap or stopper, the liquid plastic material may be caused successively to recede from and advance to a predetermined artificial level line in the cavity 7, thereby 60 depositing successive coatings of the plastic material on the lower curved end of the molding implement, which coatings, because of being successively exposed to air while being constantly exposed to heat from within the shell 8, form a 65 much thicker cohesive film layer containing relatively less of a solvent, if such is employed, than the film deposited on the exterior surface of the implement 4.

The implement 4 is also provided with an inner 70 casing 29, which functions as a partition wall to divide the space between the tube forming the inner passage 6 and the outer shell 8, so that heating or cooling fluids can be circulated, as indicated by arrows 10. The temperature controlling medium passes down along the inner side of the

outer shell 8 to the lower end thereof, where the lip of the bottle is formed and at which end a greater degree of heat transmission is preferably effected, and thence upwardly along the outer face of the tube forming the inner passage 6. 5 This arrangement for temperature control permits of quick expansion and contraction of the shell 8 during the "green" period of the plastic film and is an aid in temperature treatment of different plastic materials. It also helps in releasing the film during hot water dipping, if such expedient is used, as the implement body can be chilled and thus reduced in its dimensions relative to the expanding film body thereon.

10 The molding implement 11, Fig. 8, which is used to shape the lower portions 3 of the bottle 15 comprises a shell 12 having an inner tubular extension 13 for conducting air at desired pressures to a cavity 14 at the lower end of the molding implement. The shell 12 may be heated by electrical resistance means 15 shown at the right in Fig. 8, or by the circulation of a fluid temperature-controlling medium passing through suitable spaces or passages 16 and 17 shown at the left in Fig. 8, the latter expedient being preferred 25 for this type of molding implement.

The bottom cavity 14 of the implement 11 shapes the bottom portion of the bottle and comprises a slightly raised wall portion 18 which forms the horizontal bottom wall of the bottle 30 shown at 19 in Fig. 1. Intersecting ribs 20, Fig. 1, at the bottom of the bottle are formed in grooves 21, Fig. 8, which extend crosswise into the wall 18.

The procedure of forming the bottom wall portion of the bottle will now be described. At the 35 instant of submersion of the molding implement 11, the interior of the tube 13 is evacuated, causing the withdrawal of air from the cavity 14 and the grooves 21 through capillary ducts 22, which connect with the interior of the tube 13, so that 40 the liquid plastic material or dope will be immediately drawn by suction into the cavity 14 and the grooves 21. The plastic material which enters the grooves in the bottom wall 18 of the molding implement 11 will form the reinforcing 45 cross ribs 20 of the bottom wall 19 of the bottle, Figs. 1 and 10. These ribs will attain substantially fixed dimensions during the immersion period of the molding implement 11 by lengthwise and lateral shrinkage, due to the suction action 50 on the thin section of the relatively viscous liquid plastic material while it is being exposed to heat through the side walls of the grooves 21. This early rigidification of the ribs continues while the molding implement 11 is removed from the 55 liquid plastic material and the film thereon is solidifying or rigidifying. Thus, at the time of disengaging the formed film layer from the implement 11, air under suitable pressure may be caused to pass outwardly through the ducts 22 and thence 60 along each side of each of the ribs formed in the grooves 21 to flow between the outer surface of the wall 18 and the inner surface of the film layer formed thereon and thus to serve readily to loosen the entire lower bottle portion 3 from the implement 11. This action may be assisted at this instant by contraction of the metallic body of the implement by internal chilling thereof, as in the 65 case of the forming implement 4.

At the widest point of the upper portion 2 of 70 the bottle, there may be provided an annular rim or flange 24, Fig. 9, having a depending portion 31, these flange portions being formed at the upper portion 23, Fig. 7, of the implement 4. The rim or flange 24 is arranged to fit over an annular rim 75

25 of the lower portion 3 of the bottle and to be folded to embrace the rim 25 as indicated in Fig. 11 to form a shoulder flange 58 for the bottle, Fig. 1.

5 The rim 25 is formed at the upper end 26 of the molding implement 11, Fig. 8. For this purpose, suction is used to withdraw air from an annular cavity 27 through capillary ducts 28, causing the liquid plastic material to flow into contact with 10 the inner faces of the cavity 27.

For disengaging the film layer 3 from the implement 11, heated air or water may be forced through the capillary ducts 28 to release the rim 25 and the adjacent substantially cylindrical body 15 portion. This stripping action should take place at the same time the bottom end of the film body is being released or stripped from the cavity 14 as aforesaid.

The annular rim 25 is normally relatively thick 20 because of the tendency for the plastic material to fill the annular cavity 27, which action is to a certain extent independent of and subsequent to the suction action. Thus, the upper edge or brim portion of the hollow body or lower bottle portion 25 is the last portion to solidify.

It will be advantageous to permit the rim 25 to retain a degree of "greenness" or a greater proportion 30 of the solvent (if such be used) as it aids when sealing this rim to the flange 24.

30 Instead of the down-turned rim 25 as shown at the upper end of the bottle portion 3, Fig. 10, the rim may be flat and the down-turned border flange 30 omitted, in which case the rim should for best results be wider than that shown and be 35 interengaged in such manner with the rim parts 24 and 31 of the upper portion 2 of the bottle as to produce substantially interwoven annular grooves in the shoulder of the bottle. Alternatively the rim portion 31 may be first rolled down 40 and then folded in as shown in Fig. 11. For some uses, however, both rims to be connected together may be formed without depending border portions when the plastic material used is of such nature as to be fused, welded or coalesced into one homogeneous body by heat and pressure.

In Figs. 3 and 5, there is illustrated a bottle cap 32, which is adapted for use with a bottle mouth or lip of the type shown in Fig. 1. The cap 32 has a brim 33 which may be grasped to enable one 50 to remove the cap quickly from the bottle mouth. The cap 32 also has a stopper portion 35 which is adapted to be gripped at its lower end by the inturned edge 34 of the wall 36 of the bottle neck, which is a part of the thickened lip wall 9 55 of the bottle formed as aforesaid. The edge 34 of the bottle neck will cooperate with the stopper portion 35 of the cap 32 to form a seat therein, which is the actual sealing point. The material of which the cap is made should be flexible to 60 permit local contraction opposite the edge 34 of the bottle neck and should be elastic enough to expand or to be increased in size below the edge 34 by internal pressure in the bottle. In this way a good seal is provided between the cap 32 and the entire portion of the lip wall 9, the lower 65 end of the stopper expanding during capping, and spring tension being established by the downward push of the brim 33 on the upper end of the bottle.

70 In Figs. 4 and 6, there is illustrated a stopper cap 37 adapted for use with a bottle neck of the type shown for the bottle of Fig. 2, this cap having the additional feature of sealing with an outer lip edge 38 of the bottle which is generally indicated at 39. The cap 37 is formed with an

annular recessed portion 55 in its brim 33a. This recess, when the brim is forced past the edge 38 of the bottle, will seat itself firmly therearound, engaging therewith at the wall 57 of the recessed portion 55. In this construction, additional security is afforded as any normal internal pressure only serves to expand the bottle neck generally indicated at 56, thereby also expanding or thrusting outwardly the annular edge 38 of its mouth, which results in a tighter seal with the 10 wall 57 of the recessed portion 55 of the brim 33a of the cap.

These caps or stoppers thus afford both inner and outer seals with a bottle of elastic material. The material of which the cap is formed may be 15 any elastic stock, preferably of cellulosic composition, which may be pressed or otherwise formed to the required shape. The caps may be formed otherwise than by the processes here outlined. Also, various compositions of cork with 20 organic plastic materials and in some instances even rubber may be employed in combination with finely divided cork to form the inner contacting layer of the stopper portion of the cap and the recessed walls and brim thereof.

25 The elasticity of the material of the cap should be chosen in accordance with the elasticity or flexibility of the bottle material with which it is to be engaged. The greater the hardness of the neck portion of the bottle, the stronger the cap may be made, and vice versa. It is quite possible that a cap of this character may be desired for use with glass bottles if the necks of the bottles are constructed in accordance with the principles herein outlined for obtaining proper cooperation between the cap configuration and the bottle neck when internal pressure is active on the cap. A desirable feature of a cap of this type is the brim, which permits easy removal of the cap from the bottle.

40 The shoulder flange 58 of the bottle, aside from its stability factor, functions to support the bottle and its contents when it is being capped, the capping operation itself involving inventive features and requirements not directly related to the present invention, except that the mouth wall of the bottle must have a certain degree of firmness and the stopper portion 35 of the cap must have some elastic properties.

45 At the time of lifting the molding implement 50 out of the plastic material or dope or causing the liquid plastic material to recede, each implement is slightly tipped at an angle to the surface level of the liquid plastic material and momentarily kept in light touching contact therewith to 55 drain surplus liquid from the molding implement without dripping, after which complete withdrawal of the molding implement from the liquid is effected and the molding implement is rotated at a suitable speed to equalize the thickness of the 60 remaining deposit and spread the film coating somewhat in the region of its lower edge. At this time air or gas currents, or even steam, may be caused to impinge against the film body to facilitate removal of solvents (if such be used) from 65 the plastic film forming the bottle. Other processes of film rigidification may be practiced before, during or after rotation of the molding implement as aforesaid, depending upon the composition of the plastic material or dope and on 70 the thickness of the deposit on the forming implement.

The body portion 3 of the bottle shown in Fig. 10, may be used as a light weight drinking cup or "glass" of the tumbler type, which may be pro- 75

vided with a curved brim by appropriately shaping the annular cavity 27 of the molding implement. Such a drinking vessel is particularly advantageous for use in drug stores and other places where the sanitary features and light weight as well as the unbreakable qualities of the cup are important.

Transparent substantially tubular bodies formed without any stiffening at the neck portion, such as metallic mouth-forming parts, can be formed by the process so far outlined. The forming of the brim or edge of a substantially tubular body of the dip-formed variety appears to be entirely novel when accomplished at the same time the body is formed, which of course promotes economy and brings production within practicable limits. It also appears that no one has so far produced a flat-bottomed article with reinforcing ribs, which feature prevents warping and gives strength to the article.

The bottle 39, Fig. 2, may be formed in one piece from a liquid plastic material or dope, preferably high in solid material content. In some instances, plastic materials which are kept liquid or near liquid at relatively high temperatures may be used.

In Fig. 12 is shown a body of a liquid plastic material or dope 5 and a suction mold 40 during the approach of the latter toward the surface of the liquid plastic material or dope, the upper end or tip of a hollow tube 41 marking substantially the center point of the area of mold contact with the pool of the liquid plastic material. The tube 41 at this instant is in its lower position with its open end projected slightly above the level of the liquid plastic material 5 in the pool. As the lower surface 43 of the mold 40 around the opening 42 of the entrance cavity 51 of the mold touches the level of the liquid, the open end of the tube 41 is moved upwardly out of the liquid, while at the same time vacuum is applied to the mold cavity 44 through a plurality of passages or capillary ducts 45 from a conducting passage 46, Fig. 12, thereby causing the plastic liquid material to move upwardly into the mold cavity as shown in Figs. 13 and 14, the tube 41 also moving upwardly to about the position shown in Fig. 14. As the mold 40 is progressively filled, superficial coagulation or solidification of the plastic material takes place along the walls 50 of the mold cavity 44. The actual depth to which the surface coagulation extends depends of course upon the composition and character of the liquid plastic material. With a cellulose derivative dope and a heated mold, the vacuum in the mold will promote increased viscosity and skin cohesiveness in the surface layer of plastic material. After a certain time interval required to produce inceptive cohesiveness in the layer of the liquid plastic material in contact with the mold walls, a volume of air may be blown from the tube 41 into the body of the liquid plastic material or dope, causing a separation to take place between the cohesive surface layer of plastic material and the more liquid central body thereof. Before this action takes place, outside cross ribs 47, Figs. 2 and 14, of the bottle 39 have been formed in recessed grooves 49 of the mold body. This action takes place while the air space 48, Fig. 14, is being expanded as indicated in Fig. 15 and the central body of liquid is being expelled from the mold cavity or returned to its source. The vacuum applied as aforesaid through the mold walls is instrumental in holding the now relatively firm film layer to the walls of the mold cavity. The combined ac-

tion of the air pressure, the heat of the mold, and the suction action on the plastic layer is effective in removing solvents (if such be used) and in so fixing the internal stress factors in the film structure as to prevent subsequent warping to a large degree.

As the liquid plastic material or dope is caused to recede downwardly to a point below the actual lip wall of the bottle mold, the application of air under pressure through the tube 41, Fig. 16, may be discontinued and the hollow space within the film receptacle thus formed may be partly evacuated, which aids in removing the solvent (if such be used) from the layer of plastic material on the inner walls of the mold cavity before the liquid plastic material or dope is again introduced into the mold cavity. If the tube 41 is raised to a point close to the upper end of the mold cavity and vacuum applied therethrough, all portions of the previously formed film may again be coated. This second charge of liquid plastic material should be quickly expelled by the application of air under pressure through the tube 41 to prevent an excessively thick film layer inside the first film layer. For forming a film wall of ordinary thickness and an upper portion of the bottle body of an increased thickness, only a partial resurgence of the liquid plastic material or dope up to a point slightly past the annular shoulder wall may be required. For many types of bottles, such second coating is superfluous, particularly when reinforced bottle structures are being made. Very strong bottles may be made by this method by a single coating operation, followed by externally dipping the formed articles in a suitable coating liquid. This method is desirable in making bottles which are paneled or provided with external ribs. The external coating applied will smooth all corners and projecting points and make a good appearing bottle.

The lip 53 of the mouth of the bottle, Fig. 2, is the last portion to be formed, as indicated in Fig. 16, wherein the liquid plastic material or dope is shown substantially completely expelled from the mold cavity. In order not to disturb the lip wall 53 of the bottle as the liquid plastic material or dope is expelled from the mold cavity by the air pressure action, the entrance cavity 51 is provided, which enables the air to move the liquid plastic material transversely downwardly and outwardly away from the film layer while the air pressure forces the plastic lip formation against the mold. As the liquid plastic material or dope recedes completely from the mold cavity, a cone-shaped apron of plastic material is formed having the shape of the cavity 51, which extension may later be trimmed off from the lip portion 53 of the bottle as shown in Fig. 19.

When the mold 40 is removed from contact with the liquid plastic material, Fig. 17, the film bottle formed therein is still acted upon and held to the inner walls 50 of the mold cavity by the vacuum action through the passages 45. The inner surface of the bottle wall may now be acted upon by circulating air, heated or otherwise, introduced by any suitable blow pipe into the mold cavity and permitted to exhaust through the lower open end thereof. If desired the tube 41 may be used for this purpose.

Liquid solvent removers or film coagulating means may also be used, depending on the nature of the plastic material employed, in which case the mold may be inverted.

In forming the shoulder flange 60, Figs. 2 and 18, on the bottle body 39, heat and pressure are

combined during the "green" stage of the film walls, and the hollow rib formed as aforesaid may be compacted to form the rib 60 as shown in Fig. 18, wherein the preliminary and final steps of compacting are shown at the left and right respectively. In many instances, this expedient is not necessary as this particular bottle may be capped without excessive pressure being brought to bear on the shoulder flange, the open form of which as the article is made as aforesaid, being sufficient for many purposes. Also external ribbings may be formed to extend radially of the upper portion of the bottle 39 from the shoulder flange 60 to the vicinity of the neck portion 56. Instead of forming the shoulder flange 60 by compacting the hollow shoulder rib on the bottle, a shoulder rim, may be formed at the time of charging the mold in the same way as the cross ribs 47 by providing a rim-shaped recess in the wall 50 of the mold cavity and drawing the liquid plastic material or dope thereinto by suction. Such single ply rim may be reenforced by a number of webbings or ribs formed in grooves disposed radially in the bottle wall at spaced points above or below the proposed annular groove of the shoulder rim and at right angles thereto.

The mold 40 shown in the several views is assembled from several parts and may be constructed of any suitable metal and heated in any known way, each section thereof, however, being heated (or cooled) individually in a thoroughly enclosed way, and preferably by air.

With certain kinds of film bottle structures, depending on the nature of the plastic material or dope to be used, it will be advantageous in order to obtain the best results to subject the interior film walls to internal fluid pressure while still in the mold and externally acted upon by the vacuum action as aforesaid, although vacuum is not always needed for the purpose of equalizing density factors in the wall structure and in removing stresses or their causes.

The procedure involved is to seat a suitable nozzle (not shown) of any suitable pressure conveying means against the film covering or apron in the cavity 51 and then to charge the bottle in the mold with fluid under suitably controlled pressure to press the walls of the film bottle against the walls of the mold cavity.

The various methods and means described may of course be used in conjunction with one another or be interchanged, whenever such arrangements may be desired, to improve production methods and without departing from the spirit and scope of this invention, as for instance, the suction process may readily be employed for making the body portion 3 of the two-part bottle 1, or any number of similar shapes.

The differential pressure process described enables accurate and stable formation of thin and heavy wall containers and other hollow objects from cellulosic dopes and other plastic compounds that normally shrink or reduce in volume while being solidified and thus are susceptible to warping, by the uniform and effective removal of solvents during the shaping of articles and the fixing of the dimensions by the solvent removing means and other expedients applicable to the process and inherent therein.

For trimming off the surplus film formed on the walls of the cavity 51, a simple expedient is illustrated in Fig. 19. The bottle neck is shown as being held in a cutter block 61 while a tubular cutter 62 is caused to descend, the cutting edge 63 thereof engaging a cooperating cutting edge

64 of the block, thereby shearing the surplus film from the lip wall of the bottle and forming the finished edge 38. A number of other types of mechanisms for the same purpose may also be employed.

Certain types of container mouths can be formed by the suction process without forming a surplus apron or film, particularly such lip or edge formations where the wall is turned outwardly and then downwardly toward or in the direction of the bottle.

Wide mouth transparent containers and boxes usable for keeping fresh and displaying food products and other merchandise can also be manufactured at a relatively low cost with the processes here outlined.

Claims directed specifically to the two-part bottle shown in Fig. 1 are not included herein, but are presented in a copending application, Serial No. 629,695, filed Aug. 20, 1932, which is a division of this case. My said co-pending application also contains claims to the bottle-part 3, per se, which is separately useful as a drinking cup.

Claims directed to the caps 32 or 37, per se, or the combination of such caps with a container such as the bottle shown in Figs. 1 and 2 are to be found in another of my co-pending applications, Ser. No. 588,644, filed Jan. 23, 1932, which is a continuation in part of the present case.

Having thus described my invention I desire to claim as new and to secure by Letters Patent:

1. A bottle of cellulosic material comprising a lower portion with a conical smooth integral seamless outer surface to receive labels or the like and an upper smooth integral seamless portion of a generally conical shape but with a wavy outline and terminating in a mouth portion smaller than the body portion and having overturned curved portions around its mouth adapted to fit into a groove around the periphery of a stopper.

2. A bottle having a substantially frusto-conically shaped, one-piece upper portion of pliable cellulosic material and a smaller neck portion made up of curved overturned portions to stiffen the material at the neck and shaped to fit snugly in a groove extending around the periphery of a stopper.

3. A bottle having its upper portion of a seamless, one-piece cellulosic material, said portion having a contracted neck portion integral with said upper portion, the opening through the neck portion being bounded by the turned-over curved portion, said curved portion curving inwardly towards the neck portion and thence outwardly from the neck portion and being adapted to fit into a groove in a stopper when the groove extends around the stopper between its upper and lower ends.

4. A one piece bottle formed of pliable cellulosic material having a neck contracted in size as compared with the upper body portion, the inner surface of the neck being formed of a turned over curved portion of the material of the body portion to stiffen the material of said neck, the direction of curvature from the neck being outward both below and above the middle of the neck portion to adapt it to project into a groove around the periphery of a stopper.

5. A container having a closed end and an open end the wall structure of which is translucent, lightweight, tough and flexible and which together with certain reinforcing features associated therewith has originated from a cellulosic

solution applied to the surface of a mold, the open end of the container being constricted and shaped with an outwardly extending reinforcing flange.

5 6. A container having a closed end and an open end the wall structure of which is translucent, lightweight, tough and flexible and which together with certain reinforcing features associated therewith has originated from a cellulosic solution applied to the surface of a mold, the closed end being so configurated as to present a transverse diametrical reinforcing rib.

10 7. A bottle made of pliable cellulosic material and having an integral neck portion which tapers upwardly from the body portion to the outer end of the neck portion, the neck portion being turned over in a curve extending first inwardly thence outwardly to form a turned over portion surrounding the mouth of the bottle to strengthen 15 the pliable material around the mouth, said turned over portion of the mouth being adapted to fit into a groove around the periphery of a stopper.

20 8. A bottle having an upper integral seamless body portion and a mouth portion, a neck portion between the body and the mouth portion, said neck portion being smaller than the body portion but larger than the mouth portion, the material of the mouth portion being turned over 25 to form a smooth circular portion adapted to fit in a groove around the periphery of a stopper for the mouth.

25 9. A container of flexible wall structure and of bottle type having an upwardly tapering neck wall with an open mouth which is provided with a narrowed-in opening formed by a constriction of the wall at the upper portion of neck, said mouth being provided with a single ply brim that is turned outwardly directly from the narrow 30 point of the neck and mouth, said container having a seamless wall structure which in its entirety has originated solely from a layer of soft plastic material collected on to the walls of a mold cavity and solidified therat.

35 10. A container having a closed end and closure engaging open end that is provided with resiliently yielding inner and outer contact areas for automatically obtaining a sealing hold on any closure which is shaped to fit such areas with slight pressure, said container comprising a body 40 wall structure which is flexible and which together with single-ply rib-walls which are set at right angles to the body wall proper, has originated as an integral unit from a coating of plastic material applied to the surfaces of a mold cavity.

45 11. A bottle having walls of a seamless and

flexible structure set directly from material in fluent condition into one continuous integral piece with the wall formation at its mouth curved inwardly and thence outwardly to form a funnel-like mouth portion for the bottle.

5

12. A container, the wall structure of which is translucent, light weight, tough and flexible, set into final shape directly from plastic material in fluent condition and having a reinforcing rib on its outer surface opposite a smooth inner surface 10 and formed of the same material and at the same time as, and integral with, the wall that it reinforces.

15 13. A container having a closed end and an open end, the wall structure of which is transparent, light weight, tough and flexible, set into final shape directly from plastic material in fluent condition, and having its inner surface smooth, and a rib on its outer surface around it intermediate its ends, said rib being integral with and 20 formed at the same time as the wall which it reinforces.

25 14. A bottle flaring upward to an intermediate point and then tapering in to a mouth, the wall structure of which is translucent, light weight, 25 tough and flexible, set into final shape directly from plastic material in fluent condition, there being a reinforcing rib around the bottle at approximately the point where the outward flaring lower portion and the inward tapering upper portion meet, said rib being integral with and formed 30 at the same time as the wall which it reinforces.

35 15. A container having a closed end and the wall structure of which is translucent, light weight, tough and flexible, set into final shape 35 directly from plastic material in fluent condition, the closed end of said container being concave on its outer side and smooth on its inner side, the outer concave side being provided with reinforcing ribs integral with and formed at the same time 40 with the said end.

16. The container of claim 13 wherein an additional integral reinforcing rib is provided around the open end of said container.

45 17. The container of claim 5 wherein a circumferential rib is provided intermediate said closed end and said open end, said rib serving to reinforce said container.

50 18. A container formed of an inherently water-proof, previously unformed plastic material with relatively thin flexible walls in one seamless unit with an open top end surrounded by a brim wall, said brim wall being thicker in body section than the walls of the container and being shaped with a downwardly turned edge.
